UNITED STATES PATENT OFFICE.

WILLIAM R. CUNNINGHAM, OF BROOKLYN, OHIO.

IMPROVEMENT IN WATER-ELEVATORS.

Specification forming part of Letters Patent No. 35,013, dated April 22, 1862.

To all whom it may concern:

Be it known that I, WILLIAM R. CUNNINGHAM, of the town of Brooklyn, in the county of Cuyahoga and State of Ohio, have invented a new and useful Apparatus, being an Improved Machine for Raising Water from Wells and Cisterns and Discharging the Same; and I do declare that the following is a full, clear, and exact description of the construction and operation of the same, reference being had to the accompanying drawings, making a part of this specification, in which—

Figure 1 is a perspective view. Fig. 2 is a front view; Fig. 3, a side view; and in Fig. 4 it is shown as seen from above.

My machine consists, first, of the windlass W, with the crank 13, the rope S S, and the bucket D, these being the means used to raise the water; second, the actuating-lever F F, the deflecting-levers G G, the valve Q Q, the valve-rod M, the spiral spring P, and the inclined plane E, these being the appliances used to place the bucket over the trough A and discharge the water; third, the sliding journal-box 7, the spiral spring 8 8 8, the flange 10, and the rubber, 11, the result desired from the combination of these being the descent of the bucket to the surface of the water at a moderate speed without lowering by hand.

The drum of the windlass is constructed with a flange, 10, which serves the double purpose of preventing the rope from winding off the drum and of producing friction at its periphery with the rubber, 11.

The bucket is of conical form, and has an opening in its bottom over which the valve Q Q is placed. It is also provided with a short spout, 15, which is fastened upon its bottom and which serves to discharge the water in a compact stream in the proper direction. The bucket is further provided with two cross-bars, H H and K K, which have holes through them at I and L of sufficient size to admit the valve-rod M and allow it to move freely. Upon the valve-rod, immediately over the cross-bar K K, is placed the nut O, which fixes the distance which the valve-rod M can descend into the bucket. The rod M is connected with the valve Q Q by the chain R. The rope S S is attached to the valve-rod at N, thus making the connection between the

valve Q Q and the windlass W complete, and enabling the operator to open the valve Q Q at pleasure. The chain R is used so that when the bucket strikes the water the valve may open and the bucket fill from the bottom. The levers G G and F F are firmly set into the roller T at 14 14 and 16, the roller T is set into and supported by the sockets 18 18, and it moves freely upon its axis. The actuating-lever F F is formed with a loop, through which the rope passes, as seen at 19.

In turning the windlass the bucket is drawn up, and at the instant that the bottom of the bucket is on a level with the top of the trough A the top of the bucket comes in contact with the actuating-lever F F, as shown at y, carrying it up, giving to the roller T a backward motion. Thus a forward and upward movement is communicated to the deflecting-levers G G, indicated by the dotted lines z z, carrying with them the bucket D until it is brought against the inclined plane E, which with the levers G G form a clamp which holds the bucket firmly until the valve is opened and the water discharged. The bucket being firmly held, the valve Q Q is opened by a slight additional pressure upon the crank 13, whereby the valve-rod M and the nut O are raised, the spring P compressed, the chain R straightened, and the valve Q Q opened, permitting the water to escape through the spout 15 in the direction indicated by the blue tracing. As soon as the water is discharged from the bucket the pressure is removed from the crank 13, the levers fall back to the position shown by the dotted lines G G and F F, the rope and bucket to the dotted lines S S, the spring P expands, the valve-rod M sinks into the bucket, so that the nut O rests upon the cross-bar K K, as shown at 20, the valve closes, and the bucket descends to the surface of the water without further attention. This result is obtained by means of a self-regulating brake, the outlines of which are seen at 1 2 3.

The journal 6, upon which the windlass turns, is placed in a sliding journal-box, 7, the lower part of which is of cylindrical form, and is set inside of the spiral spring 8 8 8.

The red line 4 5 4 indicates a shoulder with which the journal-box is formed, which shoulder rests upon the spring at 5, and the journal-box is kept in its place by the parts marked

9 9, which slide in grooves of corresponding form made in the material marked 17 17.

The spring 8 8 8 is so adjusted that the weight of the water and bucket is sufficient to compress the spring 8 8 8, so that the journal-box 7 slides down and the windlass is brought to the position shown in Fig. 2, leaving a space at 21 between the flange 10 and the rubber, 11, thus allowing the windlass to revolve without friction with the rubber at 11. As soon, however, as the water is discharged and the bucket and rope permitted to assume the position shown by the dotted lines S S, the weight of the water being removed, the spring 8 8 8 expands, raising the journal-box 7 and with it the windlass W, bringing the periphery of the flange 10 into frictional contact with the rubber, 11, thus preventing a too rapid descent of the bucket.

The pressure of the spring 8 8 8 is regulated by turning the set-screw 12. If the friction at 11 were uniform during the descent of the bucket, it is plain that the motion of the bucket would be one of accelerating velocity, thereby making the utility of this part of my invention doubtful; but the friction at 11 is not uniform. The spring 8 8 8 presses with

nearly uniform force; but it has, when the bucket starts upon its descent, to support the whole weight of the bucket and rope, thereby reducing the friction at 11; but the weight of the bucket and rope is gradually removed from the spring 8 8 8 as the rope uncoils in the direction of the crank, leaving the full force of the spring 8 8 8 to be employed in producing friction at 11, thus counteracting the acceleration of motion and insuring the descent of the bucket at a gentle speed without further attention from the operator, and thus saving the time and labor of lowering it to the water by hand.

What I claim as my invention, and desire to secure by Letters Patent, is—

The self-regulating brake composed of the spring 8 8 8, the sliding journal-box 7, the rubber, 11, used in connection with the friction-flange 10, the whole being constructed substantially in the manner and for the purpose specified.

WM. R. CUNNINGHAM.
